H. Houston.

United States Patent Office.

THOMAS R. EVANS, OF PHILADELPHIA, PENNSYLVANIA.

Letters Patent No. 89,473, dated April 27, 1869.

IMPROVED SHOE-TREE.

The Schedule referred to in these Letters Patent and making part of the same.

To all whom it may concern:

Be it known that I, THOMAS R. EVANS, of Philadelphia, Pennsylvania, have invented an Improved Revolving Shoe-Tree; and I do hereby declare the following to be a full, clear, and exact description of the same.

My invention consists in the combination, with a revolving shoe-tree, (the leg of which is formed in one piece, instead of in several pieces as heretofore,) of a pawl and ratchet-wheel, by means of which the said shoe-tree can be prevented from turning, and can be held firmly in any required position, all as fully described hereafter.

In order to enable others skilled in the art to make and use my invention, I will now proceed to describe its construction and operation, reference being had to the accompanying drawing, which forms a part of this specification, and in which—

Figure 1 is a perspective view of my improved revolving shoe-tree, and

Figure 2, a sectional plan view of a portion of the same.

The horizontal spindle A, to which the shoe-tree B is secured, is arranged to turn in a tubular bearing, a, formed on the upper portion of a metal bracket, F, which is secured to the edge of a table or bench, X, shown in red lines.

To the rear end of the spindle A is secured a cog-wheel, C, against one edge of which bears a spring-plate, D, which is attached to the lower portion of the bracket F, a lug or projection, b, of this spring-plate entering the space between two of the teeth of the said cog-wheel, and preventing the latter or its spindle from turning until the lug is withdrawn.

The shoe-tree is secured to a disk, f, at the front end of the spindle A, by screws h h, a stem, i, (or continuation of the spindle,) entering an opening in the said shoe-tree, and relieving the strain upon the screws.

The shoe-tree consists of but two portions, a leg-piece, m, and toe-piece, m', the latter having a dovetailed tongue, x, adapted to a corresponding recess of the former.

The method of using the above instrument is as follows:

The toe-piece m' is first inserted into the shoe which is to be worked upon, and is followed by the leg-piece m, the two portions being connected together, within the shoe, by means of the dovetailed tongue and recess.

The shoe-tree being perfectly rigid and prevented from turning by means of the spring-pawl D and cog-wheel, the shoe can be rubbed and finished with the greatest facility, and when it is desired to slightly turn the instrument in order to work upon a different portion of the shoe, all that is necessary is to withdraw the lug b from between the teeth of the cog-wheel, and to turn the latter and shoe-tree to the required position, after which the spring-pawl is released in order that it may retain the cog-wheel as before.

An important part of my invention is the forming of the leg of the shoe-tree in one piece, instead of in several pieces with intermediate wedges, as heretofore, this plan enabling me to finish a shoe more rapidly, and with greater neatness, than where the rubbing-surface is broken and ridged by joints and wedges.

I claim as my invention, and desire to secure by Letters Patent—

The combination, with a revolving shoe-tree, of a pawl and ratchet-wheel, arranged and operating substantially as and for the purpose described.

In testimony whereof, I have signed my name to this specification, in the presence of two subscribing witnesses.

THOS. R. EVANS.
